UNITED STATES PATENT OFFICE.

JOHN W. MINOR, OF MIDDLEBOROUGH, MASSACHUSETTS.

IMPROVEMENT IN PICKET-POINTERS.

Specification forming part of Letters Patent No. 118,964, dated September 12, 1871.

To all whom it may concern:

Be it known that I, JOHN W. MINOR, of Middleborough, in the county of Plymouth and State of Massachusetts, have invented a new and Improved Picket-Pointer; and I do hereby declare that the following is a full, clear, and exact description thereof, which will enable others skilled in the art to make and use the same, reference being had to the accompanying drawing forming a part of this specification, in which—

Figure 1 represents a side elevation of my improved picket-pointer. Fig. 2 is a transverse section of the same on the line *c c*, Fig. 1.

Similar letters of reference indicate corresponding parts.

This invention relates to a new machine for pointing pickets and posts, and consists in a general arrangement of parts.

A in the drawing represents a horse or frame, supporting my improved pointing apparatus. Its upper beam or piece *a* constitutes the support for the picket *B* to be pointed. In the lower part of the frame is a slot, *b*, wherein a box or block, *d*, is held between two wedges, *e* and *f*. *C* is a forked lever, straddling the beam *A*, and pivoted, by a pin, *g*, to the block *d*. Above the beam *A* the lever carries the knife *h*, for pointing the picket.

D is an adjustable head-block, against which the end of the picket is placed. A bolt or pin, *i*, secures the slotted head-block to the upper face

of the beam *A*, but permits longitudinal adjustment of the same.

The picket to be pointed is placed upon the face of the beam *A*, with its end against the head-block. The pivot *g* of the lever *C* is adjusted higher or lower in accordance with the thickness of the picket, so as to bring the knife to the requisite height. This adjustment is produced by means of wedges or keys, *e* and *f*, which hold the block at the desired height. The head-block is adjusted toward or away from the lever, according to the taper to be cut. When the picket has been properly placed, the lever *C* is swung on its pivot so as to carry the knife through the end of the picket against the head-block. This completes one side of the picket, after which the same is turned and similarly treated until all sides have been prepared in the desired manner.

Without desiring to claim separately any of the parts composing my improved machine, what I do esteem as new is—

The forked lever *C*, carrying knife *h*, vertically-adjustable fulcrum-block *d*, and the head-block *D* secured by screw-bolt *i* applied to the supporting-beam *A*, all constructed, arranged, and operating as shown and described.

JOHN W. MINOR.
